UNITED STATES PATENT OFFICE.

EDWARD HENRY HORWOOD, OF HOBOKEN, NEW JERSEY:

UNDERWAIST.

No. 823,867.

Specification of Letters Patent.

Patented June 19, 1906.

Application filed February 17, 1906. Serial No. 301,627.

To all whom it may concern:

Be it known that I, EDWARD HENRY HORWOOD, a citizen of the United States, and a resident of Hoboken, in the county of Hudson and State of New Jersey, have invented 5 a new and useful Improvement in Underwaists, of which the following is a full, clear, and exact description.

My invention relates to the manufacture 10 of underwaists for children, youths, and misses of that class wherein the armhole-section is rendered double and likewise that portion immediately beneath the armhole.

The purpose of the invention is to improve 15 upon the construction of the underwaist for which Letters Patent were granted to me September 26, 1905, Serial No. 800,444, in such manner as to obtain all of the strength given to the garment by the former construction 20 without causing the garment to be bulky at the armpit and at the same time preserve double or reinforced surfaces where the greatest strength is desired—namely, upon vertical lines from the shoulders to the skirt or 25 waist band—and at the same time render that portion of the garment from the armpit-section of the armhole to the waistband where the least strain is exerted comparatively thin, not only promoting comfort in other ways, 30 but also rendering the garment exceedingly cool at such points.

The invention consists in the novel construction and combination of the several parts, as will be hereinafter fully set forth, 35 and pointed out in the claim.

Reference is to be had to the accompanying drawings, forming a part of this specification, in which similar characters of reference indicate corresponding parts in both 40 figures.

Figure 1 is a plan view of the improved underwaist laid flat, and Fig. 2 is a horizontal section taken on the line 2 2 of Fig. 1 and drawn upon an enlarged scale.

45 A represents the single back section of an ordinary waist, B the improved side sections which connect with the back A and with the customary front section D, and D' represents a waistband of any desired type. The back 50 and front sections A and D are single, as illustrated in Fig. 2, and the same view also shows that the major portions of the side sections B are double, said side sections being each constructed in two subsections b and b', which 55 are practically duplicates, and an intermediate one b². The side subsections b and b' are

constructed of two pieces of material 10 and 11, lying one over the other, one piece being the exact counterpart in contour of the other, while the intermediate subsection b² 60 is of a single piece of material.

In cutting the pieces or members 10 and 11 of the subsections b and b' upper curved extensions 12 and 12^a are formed, the extensions 12 being continuations of the subsections b and b', the extensions 12^a continuations of the subsections b'. These extensions are oppositely curved, constitute shoulder-straps, and define the armholes E, except those portions of said armholes which are to lie centrally beneath the armpit of the wearer, and these latter portions of the armholes are formed by the upper edges of the intermediate subsections b². The longitudinal edges of the intermediate subsections b² are straight, as are likewise the opposing or inner longitudinal edges 65 of the body portions of the outer subsections b and b', as is shown at 13 in Fig. 1, while the outer edges 14 of the said subsections b and b' are inclined downwardly in direction of their straight edges from their curved extensions or strap portions, whereby the said subsections b and b' are narrowest at their bottom edges. The body portions of the said subsections b and b' and likewise the intermediate sections b² are usually of sufficient length 70 to extend to the bottom of the garment. The outer edges of the subsections b' are connected with the front sections D by means of lap-seams 15, and the intermediate subsection b² 75 is connected with the outer subsections b and b' by lap-seams 16. The edges 14 of the subsections b which face inward or in direction of the back A are connected with said back by lap-seams 17, as is shown in Fig. 2. 80 Finally, the extension or shoulder-strap sections 12 and 12^a of each side section B are connected at their abutting ends—namely, 85 at the top of the armhole—by lap-seams 18. The armholes E are provided with the usual 90 bindings 19.

105 It will be observed that when a garment is constructed as above the armhole is thoroughly protected where the most wear is experienced, and those portions of the garments below and at the sides of the armholes extending to the waistband or to the skirt of the garment are protected against the heavy strain they are frequently called upon to sustain, while the intermediate subsections b² in 110 the side sections B being made single, and therefore thin, renders the garment exceed-

ingly pliable and comfortable from a point at the armpit-section of the armholes to the lower portion of the garment and likewise renders the garment at said points quite cool.

5 Having thus described my invention, I claim as new and desire to secure by Letters Patent—

An underwaist comprising a back and front formed of two sections, and side sections, 10 each side section being formed of outer subsections and an intermediate subsection, each outer subsection being formed of duplicate members having duplicate extensions to constitute shoulder-straps and the sides and 15 lower side portions of the armholes, the intermediate subsections being formed of a single member whose upper edge constitutes the armpit edge of an armhole, the said single subsection extending otherwise the length 20 of the outer subsections, the outer subsections

of the side sections having their body extensions stitched together and their opposing longitudinal edges stitched to the intermediate subsections, the said side sections being also stitched directly to the back and the front sections, whereby to reinforce the armholes and side portions of the garment below the armholes and provide for a thin portion beneath the armpit-sections of the armholes and corresponding portions of the sides of the 25 garment, for the purpose set forth, said thin portions of the side sections of the garment being between the reinforced portions.

In testimony whereof I have signed my name to this specification in the presence of 30 two subscribing witnesses.

EDWARD HENRY HORWOOD.
